SEWING MECHANISM FOR STITCHING
WIRE EYE FASTENERSAbe Meyer Butow, New York, N. Y., assignor to
Artistic Foundations, Inc., New York, N. Y., a
corporation of New York

Application July 14, 1939, Serial No. 284,495

4 Claims. (Cl. 112—2)

In the application of ordinary sewing machines for sewing tapes having metallic fasteners thereon, to a garment or to another piece of fabric, it has been found that the sewing machine needle frequently strikes the metal fastener, resulting in breakage of the needle and frequent interruptions of the sewing operations.

This invention relates to improvements in sewing machines having a feeding cloth-presser in which the needle and the feeding cloth-presser are adapted to move in the line of feed of the sewing machine, and an object of this invention is to provide said sewing machine with means for stitching over fastener elements such as eye loops, the said means comprising tape guiding, and intermittently engaging means so that an eye bearing tape having eye fastener elements secured thereto may be attached by stitching to a portion of a garment without danger of breaking the needle.

Another object of this invention is to provide a mechanism for attaching an eye bearing tape by stitching, the said mechanism comprising engaging and feeding means reciprocated in the head of the sewing machine and being above and free of the base, thus providing a work supporting base which is free and clear, and permitting the placing and movement of a garment or piece of fabric in all directions, and the utilization of the entire surface area of the work supporting base.

In prior practice, a cam was used for raising and lowering an oscillatable stop device. Inasmuch as sewing machines used in this art run at the high speed of about 3,000 revolutions per minute, every time the oscillating stop device hits the high spot on the cam a loud noise results. These repeated loud noises and shocks all day long are a nerve-racking experience to the operator. This invention comprises gripping and feeding mechanism for stitching over fastener means which will operate in an absolutely noiseless manner and without being a disturbing influence to the entire operating force.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a top plan view of my improved de-

vice, showing the material to be operated upon in position.

Figure 2 is a front end elevation of the sewing machine.

Figure 3 is a front elevation of a sewing machine adapted for stitching wire fastening eyes.

Figure 4 is a cross-sectional view, the section being taken as on line 4—4 in Figure 3, and showing a garment having an extensive portion to one side of a strip of eye-bearing fabric lying flat and being freely movable on the work supporting base, the garment overlying the entire base up to the overhanging arm of the sewing machine.

Figure 5 is a side elevation of the presser-foot shown in Figure 2, and showing an extension having angular teeth, each adapted for gripping an arm of an eye fastener for retaining same against backward displacement.

Figure 6 is a perspective view of a feeding cloth-presser having an auxiliary feeding extension for gripping and feeding fastener elements.

Figure 7 is a front view of the assembled feeding devices shown in Figure 6, and showing the presser-foot between the bifurcated front end of the feeding cloth-presser.

Figure 8 is a fragmentary top plan view of the sewing machine showing means for oscillating a rock-shaft which imparts alternate vertical movements to the feeding foot and to the presser-foot.

In the illustrated embodiment of the invention the numeral 10 indicates a sewing machine comprising a work supporting base 11. Mounted on the base 11 is an elongated gauge 12 having a bottom plate 13 secured by screws 14 to the base. The gauge 12 has a substantially rectangular cross-section adapted for receiving and directing a strip of eye-bearing fabric 15 to the needle or needles 16.

40 The sewing machine comprises a presser-foot 17 and means for reciprocating the presser-foot to bring the lower surface of the said foot in spaced relation above the entire area of the work supporting base 11. The sewing machine also

45 comprises a feeding foot 18 mounted for vertical and horizontal movements. The presser-foot 17 and the feeding foot 18 are mounted for alternate vertical movements to and from the base 11 by mechanism hereinafter disclosed. The feeding foot 18 and the needles 16 are given vertical and horizontal movements so as to provide an upper four-motion feeding means which cooperates with the four-motion feed-dog 19 below the work supporting base 11.

50 55 The sewing machine 10 comprises the usual

hollow standard and overhanging arm, terminating in a head 20. Journalled in the sewing machine 10 is the main actuating shaft 21, which carries the crank disk 22. The crank disk 22 is provided with a crank pin 23 connected by means of the link 24 with the lateral pin of the collar 25 clamped upon the needle bar 26 whereby reciprocatory movements in a vertical direction are imparted to said needle bar upon rotation of the main shaft 21. The needle bar 26 is journalled for reciprocation in bearings provided in the vibratory frame 27 which is pivotally supported at its upper end upon a pin 28 fixed in the head 20, whereby the frame 27 is confined to swinging movements in a vertical plane transverse to the length of the main shaft 21. The vibratory frame 27 is guided in its movements at the lower end by an angularly shaped member 29 forming a guideway in which a portion of the said frame slidably moves to and fro.

In a suitable bearing formed at the rear end of the vibratory frame 27 is slidably mounted the feed-bar 30 having at its lower end the feeding cloth-presser 18. The presser-bar 31 is slidably mounted in the head 20 and carries the presser-foot 17 at its lower end.

A rock-shaft 32 has been mounted horizontally in bearings 33 and is actuated by means of an eccentric 39 (Figure 8) on the main shaft 21. Fixed to the forward end of the rock-shaft 32 is an arm 34 having a link 35 pivotally connected thereto at its lower end by a screw 36. The opposite end of the link 35 is pivotally connected by a pin 37 to an angular lever 38 which is pivotally mounted at its fulcrum 39 to a collar 40 fixed to the presser-bar 31. One end of the angular lever 38 is pivotally connected at 41 to a link 42. The link 42 is pivotally connected by a pin 43 to the feed-bar 30.

As shown by the arrows in Figure 2, when the rock-shaft 32 is given a partial rotation to the left, the arm 34 and link 35 move to the left and move the upper portion of the angular lever 38 to the left, thereby exerting a downward pressure on the pin 39, on the collar 40, and on the presser-foot 17. The to rearward or left hand motion (as viewed in Figure 2) of the link 35 causes raising motion of the pin 41, the link 42, the feed-bar 30 and the feeding foot 18 above the base 11, and simultaneous downward movement of the presser-foot 17. When the rock-shaft 32 is partially rotated to cause the link 35 to move forward, the linkage mechanism shown in Figure 2 causes the raising of the presser-foot 17 and the lowering of the feeding foot 18. It will thus be noted that the presser-foot 17 and the feeding foot 18 are mounted for alternate vertical movements.

It is to be understood that the presser-foot 17 and the feeding foot 18 are successively raised above the base 11 a distance sufficient to permit the insertion between the base and lower surface of one of said feet of a garment and a superposed strip of eye-bearing fabric, so as to permit free and clear feeding movements of the garment and a superposed strip of eye-bearing fabric on the base.

As shown in Figure 5, the presser-foot 17 has an integral extension 44. The extension 44 has an aperture 45 horizontally disposed for receiving a headed cylindrical member 46 having a threaded end portion 47 and a nut 48 thereon. The headed end 46 has an aperture 49 therethrough for receiving the cylindrical end portion of an extension 50 facing forwardly. The underside of

the extension 50 has teeth 51. Each of the teeth 51 forms an acute angle. Each tooth has a vertical wall 52, serving for retaining the eyes 53 on the eye-bearing fabric strip 15 against movement opposite the direction of feed by the operator.

As shown in Figures 6 and 7, I have provided a gripping and feeding device 54 comprising an angularly shaped metal plate 55 having two elongated through apertures 56. One side of the feeding foot 18 has been cut away to receive the metal plate 55. Threaded holes 57 have been provided in the member 18 and in alignment with the apertures 56 in the metal plate 55. Screws 58 serve for securing the metal plate 55 to the member 18. The lower portion 60 of the metal plate 55 has teeth 61 in its underside, each of the said teeth being in the form of an acute angle and having a vertical wall 62. The teeth 61 of the metal plate 55 are similar but larger than the teeth 63 in the feeding foot 18. Each tooth 61 serves for gripping a wire arm 64 of an eye fastener 53 from opposite sides, the vertical wall 62 providing a positive feeding movement of the eye fastener while preventing backward displacement by the operator, of the material being sewn.

The teeth in the metal plate form a feed-dog or elongated feeding extension which feeds the eye-bearing strip concomitantly with the feeding of a superposed garment panel and an eye-bearing strip by the teeth in the feeding cloth-presser 19.

The additional top feeds, i. e., the teeth 63 on the feeding foot 18 and the teeth 61 on the lower portion 60 of the feeding device 54 herein disclosed, provide added feeding means to the usual lower feed-dog 19 which make it possible to operate on rubber fabrics, without stretching the material.

As shown in Figure 1, the right side of the feeding foot 18 has been made triangular. This permits the forward portion of the extension 50 to be angularly directed with respect to the direction of feed and brought to the inclined side of the feeding foot.

Inasmuch as the width of a presser-foot must be wide enough to cover the feed-dog surface, the full width of the angular portion of the presser-foot is retained, to utilize the full width of the feeding action of the feed-dog. The shape of the angular portion of the feeding foot 18 is thus determined at its rear end by the width of the feed-dog 19 and at the front end by the practical minimum of the metal to prevent breakage of the member 18 at the needle hole.

In prior practice for stitching eye-bearing fabric, mechanism was employed which was supported on the base by a bracket. This bracket is in the way of the fabric worked upon and limits the width of certain garments that may be placed on the work supporting base of the sewing machine. The mechanism herein disclosed permits of the garment material 66 worked upon being moved freely up to the overhanging head of the sewing machine. The gauge 12 guides the eye-bearing strip 15 and the folder 65 guides the folded garment material 66 without any hindrance from a large width side extension 67 of the garment material which, as shown in Figure 3, can extend all the way up to the overhanging head of the sewing machine, thus utilizing the entire area of the work supporting base.

It is to be noted that the folder 65 is supported by the base 11 of the sewing machine by means of an integral folder extension 75 having holes

through which bolts 16 pass into threaded engagement with the base.

For the purpose of timing the feeding movements of the strip of eye-bearing fabric, the means for adjusting the feeding movements of the feeding foot 18 and its eye-engaging feeding extension 54 comprises an adjustable eccentric 10, mounted on the main shaft 21. The eccentric 10 is adjustable in any well known manner upon the main shaft 21 to vary the throw of a pitman 12, Figure 3, governing the movements of the feeding devices. A variable throw eccentric which is adjustable about a main shaft of a sewing machine is shown in Patent No. 1,685,436. The relative timing between the feeding foot and a 4-motion feed-dog is shown in Patent No. 1,128,519.

As best shown in Figure 8, the rock-shaft 32 has been journaled in the bearings 33 at the rear of the machine 10. The rock-shaft 32 is parallel with the main shaft 21. Secured to one end of the rock-shaft 32 is a crank arm 77, which is pivotally connected with one end of a pitman 78, of which the opposite end has a strap embracing an eccentric 59, suitably secured upon the main shaft 21.

It is to be noted that in prior practice wherein eye-fasteners are displaced out of the path of the needle descent there is a tendency to produce an undesired ruffling effect upon the goods being sewn, with resultant bulges, wrinkles and like defects of appearance in the finished work. The mechanism herein disclosed functions to grip and feed. The gripping of the wire arm of the eye fastener by the feeding teeth provides engagement with both sides of the wire and prevents ruffling, wrinkling, bulging and like defects in the finished work.

It is also to be noted that the teeth 61 in the feeding extension 54 are coarser than the fine teeth 63 in the feeding foot 18. The teeth 61 are large enough to permit entrance between them of the wire 64 of which the eye fasteners 53 are made, and for practical purposes are about two times the length of the teeth 63.

It is also to be noted that the spacing of the stitches 71 is determined by adjusting the eccentric 10 to time the movements of the feeding devices 18, 19 and 54, of the sewing machine, so as to be in proportion to the spacing of the arms of the eye fasteners 53, and thus prevent contact of the needles 16 with the wire arms of the eye fasteners, the feeding movements being predetermined to cause stitches to be formed on either side of the wire arms.

In operation, it will be noted that the mechanism herewith disclosed operates in a simple manner. Contact between the needles of the sewing machine and the eyes of the eye-bearing fabric is avoided, thereby obviating the danger of breaking the needles or damaging the fasteners carried by the eye-bearing fabric which is being stitched to a garment. Due to the fact that the line of stitching which attaches the eye-bearing fabric to the garment passes through the loops or other portions of the fastening element the fastening members are securely attached to the eye-bearing fabric and the eye-bearing fabric itself to the garment.

In accordance with the patent statutes I have described and illustrated the preferred embodiment of my invention, but it will be understood that various changes and modifications can be made therein without departing from the spirit

of the invention as defined by the appended claims.

I claim:

1. In a sewing machine of the class described for attaching a tape carrying eye fastener elements to a garment, comprising needles having vertical and horizontal movements and a feeding foot having a bifurcated front end portion and needle holes therein, and a presser-foot having a front extension mounted for motion inside said bifurcation; the improvement comprising an extension mounted in the rear of said presser-foot and extending forwardly at one side thereof, said sideways extension having angularly shaped teeth, said feeding foot adjoining said sideways extension being angularly positioned with respect to the direction of feed to permit the toothed portion of said sideways extension to closely approach one of said needle holes, said teeth being positioned so as to grip and retain one of said eyes against undesired displacement into the path of the descending needles.

2. In a sewing machine of the class described for attaching a tape carrying eye fastener elements to a garment, comprising needles having vertical and horizontal movements and a feeding foot having a bifurcated front end portion and needle holes therein, and a presser-foot having a front extension mounted for motion inside said bifurcation; the improvement comprising an extension mounted in the rear of said presser-foot and extending forwardly at one side thereof, said sideways extension having angularly shaped teeth, said feeding foot adjoining said sideways extension being angularly positioned with respect to the direction of feed to permit the toothed portion of said sideways extension to closely approach one of said needle holes, said teeth being positioned so as to grip and retain one of said eyes against undesired displacement into the path of the descending needles.

3. In a sewing machine of the class described for attaching a tape carrying wire eye fastener elements to a garment, comprising a feeding foot and needles having vertical and horizontal movements, said feeding foot having a bifurcated front end portion and needle holes therein, a presser-foot having a front extension mounted for motion inside said bifurcation, and a lower feed-dog and means for timing said upper feeding foot and said lower feed dog; the improvement comprising an extension pivotally mounted in the rear of said presser-foot and extending forwardly at one side thereof, said sideways extension having angularly shaped teeth, said feeding foot adjoining said sideways extension being angularly positioned with respect to the direction of feed to permit the toothed portion of said sideways extension to closely approach one of said needle holes, said teeth being positioned so as to grip and retain one of said eyes against undesired displacement into the path of the descending needles.

4. In a sewing machine of the class described for attaching a tape carrying wire eye fastener elements to a garment panel, comprising a work supporting base, a feeding foot and needles having vertical and horizontal movements, said feeding foot having a bifurcated front end portion

and needle holes therein, a vertically actuated presser-foot having a front extension mounted for motion inside said bifurcation, and a lower feed-dog and means for timing said upper feeding foot and said lower feed dog; the improvement comprising an extension mounted in the rear of said presser-foot and extending forwardly at one side thereof, said sideways extension having angularly shaped teeth, said feeding foot adjoining said sideways extension being angularly positioned with respect to the direction of feed to permit the toothed portion of said sideways extension to closely approach one of said needle

holes, said teeth being positioned so as to grip and retain one of said eyes against undesired displacement into the path of the descending needles, a gauge for guiding a strip of eye-bearing fabric to said needles, a cloth folder positioned in superposed relation over said gauge and being adapted for folding and directing a garment panel to said needles, said gripping and retaining extension being vertically reciprocated relative to said work supporting base and being entirely free of said base to permit movement of said garment panel all over the area of said base.

ABE MEYER BUTOW.
